[57] CLAIM

The ornamental design for a combined header and sign support housing for a display stand, as shown and described.

DESCRIPTION

FIG. 1 is a perspective view of a combined header and sign support housing for a display stand showing our new design;

FIG. 2 is a front elevational view thereof, with the rear being a mirror image;

FIG. 3 is a side elevational view thereof, with the opposite side being a mirror image;

FIG. 4 is a top plan view thereof;

FIG. 5 is a bottom plan view thereof.

FIG. 1

FIG. 2

FIG. 3

FIG. 4

FIG. 5
